Friedrich Kugler,
By Lawyer atty.

UNITED STATES PATENT OFFICE.

JOSEF MÜLLER AND FRIEDRICH KUGLER, OF FRAUENFELD, SWITZERLAND.

MATTER-HOLDER.

1,281,633.

Specification of Letters Patent. Patented Oct. 15, 1918.

Application filed November 2, 1917. Serial No. 199,994.

To all whom it may concern:

Be it known that we, JOSEF MÜLLER, a citizen of the Republic of Switzerland, residing at Frauenfeld, Switzerland, and 5 FRIEDRICH KUGLER, a citizen of the Republic of Switzerland, residing at Frauenfeld, Switzerland, have invented certain new and useful Improvements in Matter-Holders; and we do hereby declare the following to 10 be a full, clear, and exact description of the invention, such as will enable others skilled in the art to which it appertains to make and use the same, reference being had to the accompanying drawing, and to letters and figures of reference marked thereon, which 15 form a part of this specification.

This invention relates to improvements in matter—or composition—holders acting at the same time as page-bearers. Holders 20 adapted to be put around matters or compositions for the purpose of forming packets and acting at the same time as page-bearers and comprising a strap adapted to be passed around a page are already known. 25 In some of the hitherto known holders of this kind the members for locking or closing the matter-holder, are arranged within the part of the holder acting as page-bearer.

All these known matter-holders have the 30 common drawback, that the free end or the free ends of the connecting strap to be put around the page in order to form a packet have to be threaded through locking members and that the locking or closing of the 35 matter-holder is effected by a clamping of the connecting member. The threading is, however, troublesome and takes up much time, while the clamping of the connecting members has the effect of rendering these 40 members useless in a short while. By using the hitherto known matter-holders it is moreover very difficult, and sometimes quite impossible, to obtain a loosening of the matter should it be desired to correct the composition while it is held together to a packet 45 in a resilient or elastic manner.

The object of this invention is to provide a matter-holder acting at the same time as a page-bearer, in which a threading of the 50 connecting member or holder and a clamping of the latter is avoided and which upon

the carrying out of a simple manipulation can be loosened in such a manner that, while the matter is kept together in an elastic manner, the necessary corrections in the composition may be easily carried out. 55

In the matter-holder according to this invention acting at the same time as a page-bearer and comprising a strap to be put around the page and in which the members 60 for closing or locking this holder are arranged within the part of the latter acting as a page-bearer differs in the respect from the hitherto known holders in that one end of the strap is connected to a bolt by spring 65 means, whereby this bolt is adapted to be brought at different places into engagement with the holder-part acting as page-bearer, and that the other end of said strap is also secured to the part of the holder acting as 70 page-bearer.

This invention will now be more particularly described with reference to the accompanying drawing, which illustrates a constructional example of the invention. In 75 this drawing:

Figure 1 is a plan view of a packet provided with the novel holder.

Fig. 2 is a corresponding side view seen from the left hand side of Fig. 1. 80

Fig. 3 is a bottom view corresponding to Fig. 1.

Fig. 4 is a section on the line IV—IV of Fig. 3, and

Fig. 5 illustrates a part of a locking frame 85 and four packets fixed in the latter.

1 denotes the types, which when set together to a matter, form a page. 2 denotes the heading on the top of the page. 3 is a strap having preferably the width of three picas. This strap is connected at one end to an U-shaped rail 4, 4¹ consisting of two adjacent parts. A pawl 5 provided with teeth is pivotally mounted in the shanks of a foot stick consisting of a U-shaped rail 4, 4¹ near 90 one of its ends. The end of the strap 3 projecting on the front edge of the part 4 of the rail 4, 4¹ out of the latter is pressed against the web of the rail 4, 4¹ by the teeth of the pawl 5. Near its other end the strap 100 3 is laid over and this turned over portion is clamped between the parts of a block 6

consisting of two pieces. Three helical springs 8 are fixed to a bolt 7 of the block 6, the other end of said springs engaging a bolt 9. The latter is secured to a plate 10. 5 The block 6 and the plate 10 have the same width as the strap 3 and the ends of the bolt 7 are flush with the side surfaces of the block 6, while the bolt 9 extends over the whole width of the rail 4, 4¹. The shanks 10 of the part 4 of the rail 4, 4¹ are provided with notches 11.

In order to form a packet the web of the rail 4, 4¹ is put against the bottom of the page. The strap is hereupon put over the heading 2 around the page and the block 6 is inserted between the shanks of the rail 4, 4¹. The strap 3 is tensioned by means of the plate 10 and the bolt 9 is inserted into two opposite notches 11. Hereupon plate 10 is 15 put against the helical springs 8. The page is now held tight together by means of the strap 3 and the locking or closing members of this strap are lying within the edges of the shanks of the rail 4, 4¹. In order that 20 the strap 3 may be easily pulled over the edges of the heading 2 said edges are preferably rounded off. 25

The hereinbefore described matter-holder is not removed from the page when the latter is fixed in the frame 12 (Fig. 5) as 30 the thickness of the strap is comparatively small. As the operator has only to insert the bolt 9 into two of the recesses 11 of the rail 4, 4¹ or to remove it out of said recesses, the 35 binding of the matter to a packet and the opening of the latter can be effected quicker and in a more secure manner than is the case when using the hitherto known cords. In order to correct the composition, the whole 40 packet may be removed from the frame 12 and the strap may then be loosened by inserting the bolt 9 into others of the recesses or notches 11 of the rail part 4, so that the matter is still held together. When a great 45 number of corrections have to be made the holder may be quickly loosened and afterward again be put around the page. A page 50 held together by means of the hereinbefore described holder may be inserted into or removed from the frame 12 by means of one hand only without collapsing and this even in the case when a page is comparatively large. This is a consequence of the great 55 width of the strap. Moreover, the strap 3 gives also a hold to lines, which are not exactly justified. This is particularly of importance when the packet has to be inserted into the frame 12. Finally, the pages can be taken out of the frame 12 when they have to 60 be washed, so that this frame and its webs do not have to be dipped into the washing liquid and therefore remain dry.

The contraction of the strap 3 due to its

becoming wet during the washing operation and the stretching of said strap occurring 65 during its subsequent drying are compensated by the helical springs 8, so that the strap exerts always the tension required for holding the page together. As the strap has to be dipped into a liquid it is preferably im- 70 pregnated.

Owing to the fact, that the locking members lie within the edges of the shanks of the rail 4, 4¹, these members are not in the way when the pages have to be fixed within the 75 frame 12 as the rail comes to rest with said edges on the corresponding fixing web of this locking frame 12.

The hereinbefore described holder may be used in connection with pages having very 80 different sizes and the part 4¹ may also be dispensed with, or it may be replaced by another part having the required length. The part of the strap put into the block 6 may also be replaced by another section of the 85 strap, so that the length of the latter between the parts 5 and 6 may be adapted to the size of the page, which has to be bound in a packet.

What we claim is:

1. A matter holder acting at the same time as a page-bearer, comprising a foot-stick, a strap having one end fixed to the latter, a block movable relatively to the foot-stick, the second end of the strap being fixed 95 to said block, a member adapted to be brought at different places into engagement with the foot-stick, and spring means connecting the last mentioned member to said block whereby the band is automatically 100 held taut.

2. A matter-holder acting at the same time as a page-bearer, comprising a fabric strap, a U-shaped rail adapted to act as a foot-stick and provided on its shanks with a plurality of oppositely arranged notches, a pawl pivotally mounted in said rail and adapted to press one end of the strap against the rail, a block consisting of two parts, means for pressing the latter together to clamp the second end of the strap between said parts, a bolt adapted to be brought into engagement with two opposite notches of the rail, and springs connected at one end of said bolt and at the other end to said block.

3. A matter-holder acting at the same time as a page-bearer, comprising a fabric-strap, a U-shaped rail adapted to act as a foot-stick and provided on its shanks with a plurality of opposite notches, a pawl pivotally mounted in said rail and adapted to press one end of the strap against the rail, a block consisting of two parts arranged between the shanks of the rail, means for pressing the two block-parts together for the purpose of clamping the second end of the

strap between said block parts, a bolt adapted to be brought into engagement with two opposite notches of the rail, springs connected at one end to said bolt and at the other end 5 to said block, and a holding plate pivotally mounted on the bolt for bringing the latter securely in and out of engagement with the

rail-notches, the bolt, springs and plate being arranged between the shanks of the U-shaped rail.

10

In testimony that we claim the foregoing as our invention, we have signed our names.

JOSEF MÜLLER.

FRIEDRICH KUGLER.
